UNITED STATES PATENT OFFICE

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND

CENTRAL HINGED WINDOW

Application filed December 10, 1931. Serial No. 580,067.

This invention relates to windows of the type where two sashes are provided in the frame, which sashes are pivoted relative to each other so that their central bars will move outwardly and are so connected to the frame that as the central bars are moved out the side bars of the sashes will move toward the center of the window, following approximately the line of the sash. In this application I show a particular method of making the frames for windows of this type which may also be used for ordinary casement windows and show a particular method of hinging the sashes together.

Referring to the drawings where an illustrative example is shown, Fig. 1 is an interior elevation of a window embodying my invention; Fig. 2 is a vertical section on line 2—2 of Fig. 1; Fig. 3 is a section on line 3—3 of Fig. 1; Fig. 4 is an enlarged view of the hinge mechanism taken from the outside with the sashes removed but with the attaching members or brackets for the sashes shown in dot and dash lines. Fig. 5 is a plan view of the hinge mechanism with a portion of the sashes indicated by dot and dash lines and the frame shown in section, and Fig. 6 is a sectional view through the sill showing one of the sashes in the position indicated in Fig. 5.

In the form of window here shown, the side members or jambs are each made of two bent members. The inner one of these has an outwardly extending portion 10 and a hook shaped portion 12. Welded into the back of the hook shaped portion 12 is a second member 14 which is L-shaped with its outside part slightly bent outwardly. Felt 16 is positioned in the pocket formed by these two members. The top or lintel member of the frame comprises a member 18 similar in shape to the inner members at the sides but very considerably higher than those members are wide. Welded to it is an L-shaped member 20 and to these two members may be welded a member 22 shaped to form a drip apron 24. The sill is here shown as made up of a single member 26 substantially similar in shape to member 18 of the lintel. A vertical bar 27 connects member

26 and member 18 at the center of the window.

The sash frames are formed of made-up tubular sections, all of which are substantially identical. Each of these sections comprises an L-shaped member 28 in which is welded a member 30 having its ends parallel with the sides of member 28 and its central portion bent to be parallel with but spaced away from member 28 to form a rigid tubular bar. If desired, the end of the longer leg of member 28 may be bent in as shown in the drawings to overlie the edge of member 30. The arrangement of these two members as shown forms a very rigid bar with an appropriate glass rabbet and an appropriate recess for flexible member 32 into which may be snapped a glass stop 34 as explained in my co-pending application, Ser. No. 503,167, filed December 18, 1930. Attached to the outside of member 28, forming the bottom rail of each sash, is a plate 35 and a similar plate 37 is attached to the outer face of member 28, forming the top rail of the sash.

One of the sashes, here designated as sash 36, is provided with a plate 38 which will overlie the other sash 40 when the window is closed, and sash 36 is also provided with felt weather stripping 42 held in place by a metal clip 44. To cooperate with this sash 40 has an angle member 46, the edge of which is adapted to press into the felt 42 when the window is closed, further to protect the window against weather. The lintel member 18 and sill member 26 may be provided with felt weather stripping 48 held in place by metal clips 50.

The sashes are connected to the window and to each other by an arrangement of the type known as a lazy tongs which is so constructed that it will fold up flat. One of these devices is provided at the top and a similar device is provided at the bottom of the window, but as the two are identical, only the bottom one will be described in detail. Near the center of each sash a bracket 52 is attached to the inner face of plate 35. Pivoted to bracket 52 of sash 40 is a forked arm 54. The lower branch of this fork 56 is offset

- as indicated at 58 and is pivoted directly to the bottom of member 26, while the upper branch 60 of this fork is pivoted to a bracket 62 mounted on the outer face of member 26.
- 5 This fork may conveniently be made as a bronze casting, and to save metal the upper fork and the part where the two forks meet may be composed of spaced bars, but this is not essential.
- 10 Pivoted to bracket 52 of sash 36 is a forked arm 64 similar to but not identical with forked arm 54. The bottom branch 66 of this member pivots about the same pivot as offset portion 58 of fork 54 and the upper 15 branch is pivoted to bracket 62 on the same pivot which is used for attaching fork 54. Between the branches of these forks are pivoted a second pair of bars 70 and 72. Bars 70 and 72 are pivoted together at 74. The 20 upper bar 70 is here shown as pivoted to a bracket 76 carried by sash 40 and at the other end is pivoted to the upper branch of fork 64. The lower bar 72 in like manner is pivoted to a bracket 78 carried by sash 36 and 25 to the upper branch 60 of fork 54.

By this arrangement, when the windows are closed, the two forks 54 and 64 will form a straight line, with the bars 70 and 72 one above the other and between the branches of the forks. When either sash is pushed out, the other sash will travel with it due to the lazy tongs effect and the sashes will be adequately supported by the forks and bars described. Also this structure has one added 30 advantage. Windows of this type are frequently used in institutions such as sanitariums and hospitals where precautions have to be taken against patients throwing themselves from the window. The forks 54 and 64 35 and the bars 70 and 72 serve to form a net work filling the space between the sashes when the window is open to the position shown in Fig. 5.

In view of the fact that sash 36 carries 40 the extension plate 38, it is desirable that this sash be pushed open first. Accordingly this sash is here shown as provided with the operating handle. This handle 79 is pivoted to the sash near the center of the window and 45 is provided with an integral hooked portion 80 adapted to engage lug 82 carried by the bar 27. To open the window the handle 79 is swung to the right and then on pushing against the handle both sashes will open. 50 To close the window, handle 79 is pulled in and then swung to the left until hook 80 engages lug 82.

What I claim is:

1. In combination with a window frame, 60 two sashes, and hinge mechanism connecting such sashes with the frame adjacent its vertical axis comprising a member pivoted to each sash and pivoted to the frame along a common axis, and a second pair of members 65 pivoted together intermediate their ends and

each pivoted at one end to a sash and at its other end to that one of said first members which is pivoted to the other sash in such a way that when the sashes are open the sashes and said members will, in all positions, substantially define four parallelograms. 70

2. A structure as specified in claim 1 in which said pivoted members are adapted to be folded into substantially one straight line. 75

3. A structure as specified in claim 1 in which a set of such pivoted members is connected to the sashes near but not above their tops in a plane above the bottom of the lintel member of the window frame and another set of such members is connected to the sashes near but not below their bottoms in a plane below the top of the sill member of the window frame, so that when the window is closed said hinge mechanisms will be embraced between the sashes and window frame. 80 85

4. In combination with a window frame, two sashes opening horizontally and hinge mechanism connecting such sashes with the frame comprising a member pivoted to each sash at approximately equivalent points thereof and to the frame upon a common axis, each of said members being approximately of the same length and being forked at the end pivoted to the frame, and a second pair of members each approximately of the same length and pivoted together midway their ends and each pivoted at one end to a sash and at its other end to one of the first members so that when the sashes are opened horizontally the second pair of members 90 maintains the sashes approximately equidistant from the frame and so that when the sashes are closed said second pair of members folds substantially within the forked ends of the first pair, and all of said members are 95 folded substantially in one straight line. 100 105

In testimony that I claim the foregoing, I have hereunto set my hand this 10th day of November 1931.
